CONFECTION

Frank V. Liberatore, 592 Crescent St.,
Brooklyn, N.Y. 11208

Filed Jan. 27, 1969, Ser. No. 15,504

Term of patent 14 years

Int. Cl. D1—02

U.S. Cl. D1—22

Fig. 1

Fig. 2

Fig. 3

The side opposite that shown in FIGURE 1 is the same as that shown in FIGURE 1.

I claim:

The ornamental design for a confection, as shown and described.
